METALWORKING MACHINE

John J. McGlone, Harvey, and Robert I. Anderson, Chicago, Ill., assignors to Whiting Corporation, Harvey, Ill., a corporation of Illinois

Original application November 21, 1942, Serial No. 466,514. Divided and this application September 3, 1943, Serial No. 501,115

18 Claims. (Cl. 153—29)

The present invention relates generally to machines for working metal in the form of sheets or plates. More particularly the invention relates to that type of metal working machine which serves to carry out or effect a flanging operation and embodies: (1) a C-shaped combined housing and supporting structure; (2) a lower shaft which is disposed at the outer extremity or end of the bottom arm of the structure and extends upwardly and outwardly at approximately an angle of 45° with respect to the horizontal, a vertically movable head at the outer end of the top arm of the structure; (3) an upper shaft on the head which extends inwardly and downwardly at substantially a 45° angle and has its inner end disposed normally over and adjacent the outer end of the lower shaft; (4) power driven mechanism including gearing and drive shafts within the structure for conjointly driving the upper and lower shafts in opposite directions; (5) a pair of complementary, coacting flanging rolls which are mounted on the upper and lower shafts, respectively; and (6) a flanging hold-down attachment in the form of a pair of arms which have rollers thereon for holding down and preventing upward bulging of the central portion of the work during drive and operation of the flanging rolls.

One object of the invention is to provide a metal working machine of this type which is an improvement on, and has certain advantages over previously designed machines for the same purpose, and is characterized by the fact that it includes a novel mount whereby the flanging hold-down attachment is supported so it may be quickly and readily adjusted with respect to the flanging rolls.

Another object of the invention is to provide in connection with a metal working machine of the type under consideration a flanging hold-down attachment of new and improved form.

Other objects of the invention and the various advantages and characteristics of the present metal working machine will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a fragmentary side view of a metal

working machine embodying the invention showing the improved flanging hold-down attachment in place on the novel mount;

Figure 2 is a plan view of the machine, parts being broken away and other parts being shown in section for illustrative purposes;

Figure 3 is an enlarged horizontal section taken on the line 3—3 of Figure 1 and showing the flanging hold-down attachment in its operative position;

Figure 4 is an enlarged plan view of the flanging hold-down attachment;

Figure 5 is a transverse section taken on the line 5—5 of Figure 4 and illustrating in detail the construction and design of such attachment; and

Figure 6 is a side view of the flanging hold-down attachment.

The machine which is illustrated in the drawings constitutes the preferred form or embodiment of the invention. It is adapted to carry out or effect flanging of pieces of sheet or plate metal and includes a pair of complementary coacting flanging rolls 8 and 9, a flanging hold-down attachment 10, and a mount 11 for the attachment. The flanging rolls 8 and 9 are adapted to be used together with the flanging hold-down attachment 10 when it is desired to use the machine to form downturned marginal flanges on circular or disc-like work pieces.

The machine, with the exception of the attachment and the mount 11 therefor, is of conventional or standard construction and comprises a C-shaped combined housing and supporting structure 12, a lower roll carrying shaft 13, a movable head 14, an upper roll carrying shaft 15 on the head, and mechanism for conjointly driving the two roll carrying shafts. The combined housing and supporting structure comprises a hollow bottom arm 16, a hollow top arm 17 and a hollow connecting part 18 and is preferably in the form of a one-piece casting. The bottom arm 16 of the structure has a flat top surface 19 and is so designed or constructed that the bottom portion thereof serves as a base for supporting the machine in an upright position on the floor or foundation of the establishment in which the machine is used. The top arm of the combined housing and supporting structure overlies, and is spaced a substantial distance from, the bottom arm 16 and is connected to the latter by way of the connecting part 18. The lower roll carrying shaft 13 is journaled in a bearing 20 at the outer extremity or end of the bottom arm 16 of the structure 12 and extends upwardly and

outwardly at an angle of approximately 45° with respect to the horizontal. The lower end of this shaft is housed within the bottom arm 16 of the structure 12 and the upper end is exposed and is adapted to carry the flanging roll 9. The head 14 carries the upper shaft 15 and overlies the upper or outer end of the lower shaft 13. It is mounted for vertical sliding movement in a guideway 21 in the outer extremity or end of the top arm 17 and is adapted to be raised or lowered by way of an upstanding screw shaft 22. This screw shaft, as shown in Figure 1, extends through a vertical internally threaded socket in a bracket 23 on the upper portion of the top arm 17 of the structure 12 and has a hand wheel 24 fixed to its upper end. The lower end of the screw shaft is operatively connected to the upper portion of the head 14 so that the screw shaft is rotatable relatively to the head while at the same time the head is connected to the shaft so as to move vertically in connection with such movement of the screw shaft. When the hand wheel 24 is rotated in one direction the head, together with the upper shaft 15, slides downwards towards the outer end of the bottom arm 16 of the structure 12 and when the hand wheel is reversely rotated the head and the upper shaft are caused to slide upwards in a rectilinear course. The upper shaft 15 is journaled in a bearing 25 on the lower portion of the vertically movable head 14 and extends downwardly and inwards at substantially a 45° angle, as shown in Figure 1. The lower or inner end of the upper shaft is adapted to carry the flanging roll 8. The mechanism for conjointly driving the two shafts 13 and 15 comprises an electric motor 26 on the upper rear corner of the combined housing and supporting structure 12, a horizontally extending drive shaft 27 in the upper rear portion of the structure 12, a horizontally extending shaft 28 in parallel relation with the drive shaft 27, change speed gearing 29 between the two last mentioned shafts, a horizontally extending driving shaft 30 in the top arm 17 of the structure 12, a horizontal driving shaft 31 in the bottom arm 16, clutch controlled gearing 32 for driving the drive shaft 30 from the driven shaft 28, a gear train 33 for driving the driving shaft 31 from the driving shaft 30, a pair of meshing bevel gears 34 and 35 between the front end of the driving shaft 30 and the upper outer end of the upper roll carrying shaft 15 for driving the latter shaft from the former shaft, and a pair of meshing bevel gears 36 and 37 between the front end of the driving shaft 31 and the inner end of the roll carrying shaft 13 for driving the latter shaft from said driving shaft 31. The electric motor 26 is drivably connected to the drive shaft 27 by way of a pinion 38 and a gear 39. The change speed gearing 29 between the driving shaft 27 and the driven shaft 28 is in the form of pairs of meshing gears on the two last mentioned shafts and is controlled by a key (not shown) which is slidably mounted in a horizontal keyway 40 in the driven shaft 28 and is adapted, in response to longitudinal adjustment thereof, to lock one of the gears on the driven shaft 28 for drive by the gear on the driving shaft that is in mesh therewith. Adjustment of the key is effected by way of mechanism including a hand lever 41. The clutch controlled gearing 32 is in the form of a loose pinion 42 on the rear end of the driven shaft 28 and a fixed gear 43 on the rear end of the driving shaft 30. The clutch for controlling

such gearing comprises a driving clutch member 44 which is slidably and drivably mounted on the rear extremity of the driven shaft 28 and a driven clutch member 45 which is in opposed relation with the clutch member 44 and is fixed to the pinion 42 of the gearing 32. The clutch member 44 is shifted into and out of engagement with the clutch member 45 by way of mechanism including a hand lever 46 on the front or outer end of the top arm 17 of the combined housing and supporting structure 12. When it is desired to use the machine the hand lever 41 is manipulated so as to bring into operative position the desired pair of gears of the change speed gearing 29. Thereafter the electric motor 26 is started and this results in drive of the driven shaft 28 from the drive shaft 27 through the medium of the change speed gearing 29. After the motor 26 has reached its normal speed the clutch member 44 is shifted into engagement with the clutch member 45 by manipulation of the hand lever 46. Upon engagement of the two clutch members the driving shafts 30 and 31 operate conjointly to drive the roll carrying shafts 15 and 13, respectively. The gearing is so designed that the roll carrying shaft 15 is driven in a clockwise direction when viewed from the front of the machine and the lower roll carrying shaft 13 is driven in a counterclockwise direction.

The mount 11 serves as a medium or instrumentality for adjustably supporting the flanging hold-down attachment 10, and consists of a pair of guide rods 47 and 48. These two rods are arranged in parallel relation and extend horizontally. They are disposed at opposite sides of the combined housing and supporting structure 12 and are in straddled relation with the bottom arm 16 of said structure. The guide rod 47 is located at the right-hand side of the machine as viewed in Figures 2 and 3. The rear end of said guide rod 47 is mounted in a horizontal, open-ended socket 49 in a horizontally elongated member 50. The latter has a flat upper portion which underlies, and is connected to, the horizontal leg of an angle bracket 51. The vertical leg of such angle bracket fits against, and is connected to, the connecting part 18 of the combined housing and supporting structure 12. Set screws 52 are disposed in threaded holes in the outer side portion of the member 50 and serve releasably to hold the rear end of the guide rod 47 in the socket 49. The front end of the guide rod 47 fits within a horizontal, open-ended socket 53 in one end of a horizontally elongated bracket 54 and is releasably secured in place by means of a set screw 55 which extends through the outer side portion of said bracket. The central portion of the bracket 54 fits against, and is connected to, the outer or front end of the bottom arm 16 of the structure 12. The guide rod 47 has a flat 56 on the bottom thereof and is normally rigidly held in place by way of the set screws 52 and 55. When the set screws are loosened the guide rod 47 may be removed from the sockets 49 and 53 by sliding it forwards beyond the bracket 54. The socket 52 in the bracket 54 is axially aligned with the socket 49 in the member 50. The guide rod 48 is on the left-hand side of the machine as viewed in Figures 2 and 3. It is disposed in the same horizontal plane as the guide rod 47 and has the rear end thereof mounted in a horizontal open-ended socket 57 in a horizontally elongated member 58. Such member has a flat upper portion which underlies, and is bolted to, the horizontal leg of an angle bracket 59. The vertical leg of

the angle bracket 59 fits against, and is bolted to, the adjacent side of the connecting part 18 of the combined housing and supporting structure 12. Set screws 60 extend through threaded holes in the outer side portion of the member 58 and serve releasably to hold the rear end of the guide rod 48 in the socket 57. The front end of the guide rod is mounted in a horizontal open-ended socket 61 in the other end of the bracket 54 and is releasably secured in place by a set screw 62 which extends through a threaded hole in the outer side portion of the part of the bracket 54 that defines the socket 61. Said socket 61 is axially aligned with, and the same in diameter as, the socket 57. When the set screws 60 and 62 are released the guide rod 48 may be removed from the sockets 57 and 53 by sliding it forwards. Said guide rod 48 has a flat 63 on the bottom thereof.

The flanging rolls 8 and 9 and the flanging hold-down attachment 10 are employed or utilized when the machine is used marginally to flange work pieces in the form of sheet or plate metal discs. The flanging roll 8 is removably mounted on the inner lower end of the upper shaft 15 and has in the periphery thereof an annular groove of V-shaped cross section. The wall portions that define the groove are disposed at right angles to one another, as shown in Figure 6. The other coacting flanging roll, that is, the roll 9 is removably mounted on the upper outer end of the lower shaft 13 and has a bead type periphery of V-shaped cross section. The two wall portions of the roll 9 that form the bead are disposed at right angles to one another and are adapted to fit within the annular groove in the roll 8 in connection with a flanging operation, as shown in Figure 6. During a flanging operation the work piece is placed on the flanging roll 9 and then, in connection with drive of the machine, the roll 8 is lowered slowly and progressively toward the roll 9 for flange forming purposes. In connection with a flanging operation the disc-like work piece rotates due to rotation of the rolls and thus the entire margin of the piece is formed into a down-turned right angle flange at the conclusion of the flanging operation. The attachment 10 serves as a medium for preventing upward deflection or bulging of the central portion of the work piece during flanging of the margin of the piece. It is in the form of a unit and consists of a horizontally elongated saddle type bracket 64, a shaft 65, a pair of sleeves 66 on the shaft 65, a pair of arms 67 on the sleeves, and a plurality of rollers 68 on the arms. The bracket 64 extends transversely across the bottom arm 16 of the combined housing and supporting structure 12 and has at the ends thereof downwardly facing grooves 69 of semi-circular cross section for slidably receiving the upper portions of the guide rods 47 and 48. Two cap members 70 underlie, and are bolted to, the ends of the bracket 64 and these have upwardly facing grooves 71 of semi-circular cross section for slidably receiving the bottom portions of the two guide rods 47 and 48. Upstanding set screws 72 in the central portions of the cap members 70 serve when tightened to hold the flanging hold-down attachment 10 against sliding movement with respect to the guide rods 47 and 48. As shown in Figure 5, the upper ends of these set screws are adapted to engage the flats on the bottom portions of the guide rods. The grooves 69 at the ends of the bracket 64 and the upwardly facing grooves 71 in the cap members 70 define cylindrical, open-ended sockets which are of slightly greater diameter than the

guide rods and permit the bracket, in connection with use of the attachment 10, to be slid back and forth on the guide rods into any desired position. The shaft 65 is disposed above, and in parallel relation with, the saddle type bracket 64 and is supported for vertical adjustment by way of a pair of eye bolts 73. The latter comprise eyes and depending threaded shanks and are located at the ends of the bracket 64. The eyes of the eye bolts encircle the ends of the shaft 65 and form bearings whereby said shaft is permitted to rock back and forth. The shanks of the eye bolts extend loosely through apertured lugs 74 on the ends of the saddle type bracket 64 and carry upper nuts 75 and lower nuts 76. The upper nuts rest on the upper surfaces of the lugs 74 and the lower nuts serve as lock nuts. By loosening the lower nuts 76 and conjointly turning the upper nuts 75 vertical adjustment of the shaft 65 may be effected. When the shaft is vertically adjusted to the desired extent tightening of the lower nuts 76 will lock it in place against vertical displacement. The sleeves 66 are mounted in spaced relation on the central portion of the shaft 65 and are held against rotation relatively to the shaft by way of keys 77 which are connected to, and project outwards from, the shaft and fit within keyways 78 in the sleeves. The key and keyway connections between the sleeves and the shaft permit the sleeves to be adjusted to and from one another while maintaining the sleeves against rotation relatively to the shaft. The rear portions of the sleeves 66 are provided with set screws 79 for locking the sleeves against longitudinal movement on the shaft and the front portions of the sleeves are provided with forwardly extending, substantially horizontal lugs 80. The arms 67 of the flanging hold-down attachment 10 normally extend horizontally. They project forwards from the sleeves 66 and have the rear ends thereof positioned on top of the lugs 80. Vertically extending bolts 81 extend through aligned holes in the lugs 80 and the rear ends of the arms 67 and form pivots whereby the arms may be swung to and from one another (see Figure 4). When the bolts 81 are tightened the arms are clamped in place. When such bolts are loosened the arms may be swung to or from one another, as previously pointed out. The outer ends of the arms 67 are in the form of spindles and serve rotatably to support the rollers 68. Preferably each arm 67 is provided with a longitudinal series of abutting rollers. Collars 82 are mounted on the extreme front ends of the arms 67 and serve to hold the rollers in place. When the attachment 10 is in its operative position, as shown in Figures 4 and 6, the roller carrying arms 67 are located at one side of, but slightly above, the flanging roll 9 on the shaft 13 and engage the work piece on such roll so that in connection with a flanging operation the central portion of the work piece cannot bulge upwards. In connection with a flanging operation the central portion of the work piece being flanged exerts upward pressure on the rollers tending to rock the shaft 65 in a clockwise direction as viewed in Figure 6. In order releasably to lock the shaft 65 against such rocking movement a latch 83 is provided. This latch comprises a sleeve 84 and an eye bolt 85. The sleeve is keyed or otherwise fixedly secured to the end of the shaft 65 that overlies the guide rod 47, and has a rearwardly extending lug 86. The eye bolt 85 is disposed beneath the lug 86 and is pivotally supported by a pin 87 so that it may be swung back and forth between an operative

position wherein it extends upwards and is in substantially dead center relation with the sleeve 84 and an inoperative position wherein it extends rearwards and permits the shaft 65 to rock in a clockwise direction as viewed in Figure 6. The pin 87 extends through the eye of the eye bolt 85 and is carried by a pair of laterally spaced upstanding lugs 88 on the end of the saddle type bracket 64 that is beneath the sleeve 84. The outer or distal end of the shank of the eye bolt is provided with a lug engaging abutment type nut 89 and this is normally locked in place by a jam nut 90. A tension spring 91 serves to urge the eye bolt into its operative or latching position. One end of this spring is connected to a screw 92 on the eye of the eye bolt and the other end of the spring is anchored to a screw 93 on the bracket 64. In connection with a flanging operation the work piece is properly positioned on the lower flanging roll 9. Thereafter the shaft 65 is rocked in a counterclockwise direction as viewed in Figure 6 in order to bring the rollers 68 into contact with the central portion of the top surface of the work piece. As soon as the shaft is so rocked the eye bolt 85 is swung upwards into its operative position wherein the nut 89 underlies the lug 88. After latching of the shaft 65 in place the machine is started and the upper flanging roll 8 is fed downwards by proper turning of the hand wheel 24. During the flanging operation the rollers 68 prevent upward deflection or bulging of the central portion of the work piece, as heretofore pointed out. At the conclusion of a flanging operation the eye bolt 85 is swung rearwards into its inoperative position in order to release the shaft 65 so that it may be rocked in a clockwise direction as viewed in Figure 6 for roller releasing purposes. Adjustment of the nut 89 on the shank of the eye bolt 85 serves to vary the locked position of the shaft 65 and the roller carrying arms 67. In order to facilitate swinging of the roller equipped arms for a flanging operation the shaft 65 is provided with a radially extending hand lever 94. The flanging hold-down attachment 10 may be adjusted to function in connection with a work piece of any particular diameter or thickness by sliding the bracket 64 either backwards or forwards on the guide rods 47 and 48, raising or lowering the shaft 65, and shifting the sleeves 66 to or from one another on the shaft 65. The flanging hold-down attachment may be removed from the mount 10 by releasing the guide rods 47 and 48, then sliding such rods forwards and thereafter sliding the attachment off the free rear ends of the guide rods.

The herein described metal working machine is highly efficient in operation due to the specific design and arrangement of the flanging hold-down attachment 10 and its mount 11. The mount permits of ready adjustment and removal of the attachment. The attachment is simple in construction and design and hence may be manufactured or produced at a low cost.

The invention is not to be understood as restricted to the details set forth since these may be modified within the scope of the appended claims without departing from the spirit and scope of the invention.

This application is a division of an application filed by us on November 21, 1942, Serial 466,514.

Having thus described the invention, what we claim as new and desire to secure by Letters Patent is:

1. In a metal working machine of the character described, the combination with a C-shaped supporting structure, and a pair of power driven shafts mounted one at the outer end of the bottom arm of the structure and the other at the outer end of the top arm of said structure, and having certain ends thereof disposed adjacent one another and provided with complementary coacting flanging rolls, of a pair of horizontal guide rods mounted on the structure and positioned along and outwards of opposite sides of one of said arms, and a flanging hold-down attachment comprising a horizontally elongated bracket extending transversely across said one arm and having the ends thereof slidably mounted on the rods so that it is slidable to and from the rolls, and a pair of laterally spaced arms projecting from the bracket in the direction of said rolls, mounted so they are conjointly shiftable with said bracket, and adapted to overlie the top surface of a work piece during a flanging operation.
2. In a metal working machine of the character described, the combination with a C-shaped supporting structure, and a pair of power driven shafts mounted one at the outer end of the bottom arm of the structure and the other for vertical adjustment at the outer end of the top arm of said structure, and having certain ends thereof positioned adjacent one another and provided with complementary coacting flanging rolls, of a pair of horizontal guide rods mounted on the structure and positioned along and outwards of opposite sides of said bottom arm, and a flanging hold-down attachment comprising a horizontally elongated bracket extending transversely across said bottom arm and having the ends thereof removably connected to said rods and also slidably mounted on said rods so that it is slidable to and from the one shaft, and a pair of horizontal laterally spaced arms projecting from the bracket in the direction of said one shaft, mounted so that they are shiftable with said bracket, and adapted to overlie the top surface of a work piece during a flanging operation.
3. In a metal working machine of the character described, the combination with a C-shaped supporting structure, and a pair of power driven shafts mounted one at the outer end of the bottom arm of the structure and the other for vertical adjustment at the outer end of the top arm of said structure, and having certain ends thereof positioned adjacent one another and provided with complementary coacting flanging rolls, of a pair of horizontal guide rods mounted on the structure and positioned along and outwards of opposite sides of said bottom arm, and a flanging hold-down attachment comprising a horizontally elongated bracket extending transversely across said bottom arm and having the ends thereof slidably mounted on the rods, and a pair of horizontal laterally spaced arms projecting from the bracket in the direction of said one shaft, mounted so that they are conjointly shiftable with said bracket and are also adjustable horizontally to and from one another, and adapted to overlie the top surface of a work piece during a flanging operation.
4. In a metal working machine of the character described, the combination with a C-shaped supporting structure, and a pair of power driven shafts mounted one at the outer end of the bottom arm of the structure and the other for vertical adjustment at the outer end of the top arm of said structure, and having certain ends there-

of positioned adjacent one another and provided with complementary coacting flanging rolls, of a pair of horizontal guide rods mounted on the structure and positioned along and outwards of opposite sides of said bottom arm, and a flanging hold-down attachment comprising a horizontally elongated bracket extending transversely across said bottom arm and having the ends thereof slidably mounted on the rods so that it is shiftable to and from the one shaft, and a pair of horizontal laterally spaced arms projecting from the bracket in the direction of said one shaft, pivotally supported to swing horizontally to and from one another, and adapted to overlie the top surface of a work piece during a flanging operation.

5. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a horizontally elongated bracket extending across said bottom arm and having the ends thereof slidably mounted on the rods so that it is shiftable to and from the one shaft, a horizontally elongated element overlying and extending parallel to the bracket and connected to said bracket for vertical adjustment, and a pair of horizontal laterally spaced arms connected to the element, projecting in the direction of said one shaft, and adapted to overlie the top surface of a work piece during a flanging operation.

6. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a horizontally elongated bracket extending across said bottom arm and having the ends thereof mounted on the rods, a horizontally elongated element overlying and extending parallel to the bracket and connected to said bracket for vertical adjustment, and a pair of horizontal laterally spaced arms connected to the element so that they are adjustable horizontally to and from one another, projecting in the direction of said one shaft, and adapted to overlie the top surface of a work piece during a flanging operation.

7. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed

adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a horizontally elongated bracket extending across said bottom arm and having the ends thereof slidably mounted on the rods so that it is shiftable to and from the one shaft, a horizontally elongated element overlying and extending parallel to the bracket and connected to said bracket for vertical adjustment, and a pair of horizontal laterally spaced arms having rollers mounted rotatably thereon, pivotally connected to said element so as to swing horizontally to and from one another, projecting in the direction of said one shaft, and adapted to have the rollers overlie and engage the top surface of a work piece during a flanging operation.

8. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a horizontally elongated bracket extending across said bottom arm and having the ends thereof mounted on the rods, a horizontal rock shaft carried by, overlying and extending parallel to, the bracket, a pair of laterally spaced arms connected to the rock shaft and adapted when said rock shaft is rocked in one direction to assume an operative position wherein they overlie the top surface of a work piece during a flanging operation, and releasable means for preventing reverse rocking of the rock shaft when the arms are in their operative position.

9. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a horizontally elongated bracket extending across said bottom arm and having the ends thereof mounted on the rods, a horizontal rock shaft overlying and extending parallel to the bracket and connected to said bracket for vertical adjustment, and a pair of laterally spaced arms connected to the rock shaft and adapted when said rock shaft is rocked in one direction to assume an operative position wherein they overlie the top surface of a work piece during a flanging operation, and releasable means for preventing reverse

rocking of the rock shaft when the arms are in their operative position.

10. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a horizontally elongated bracket extending across said bottom arm and having the ends thereof mounted on the rods, a horizontal rock shaft overlying and extending parallel to the bracket and connected to said bracket for vertical adjustment, a pair of laterally spaced arms having rollers rotatably mounted thereon, connected pivotally to the rock shaft to swing to and from one another, and adapted when the rock shaft is rocked in one direction to assume an operative position wherein the rollers overlie and engage the top surface of a work piece during a flanging operation, and releasable means for preventing reverse rocking of the rock shaft when the arms are not in their operative position.

11. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a horizontally elongated bracket extending over and across the bottom arm and having the ends thereof slidably mounted on the rods so that it is shiftable to and from the one shaft, a horizontal rock shaft overlying and extending parallel to the bracket and connected to said bracket for vertical adjustment, and a pair of laterally spaced arms adjustably connected to the rock shaft so that they are shiftable to and from one another and adapted when the rock shaft is rocked in one direction to assume an operative position wherein they overlie the top surface of a work piece during a flanging operation, and releasable means for preventing reverse rocking of the rock shaft when the arms are in their operative position.

12. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment

comprising a horizontally elongated bracket extended over and across said bottom arm, having the ends thereof mounted on the rods, and provided with a pair of upstanding eye bolts with the eyes thereof at the top, a horizontal rock shaft overlying and extending parallel to the bracket and having the ends thereof journalled in the eyes of the bolts, a pair of laterally spaced arms connected to the rock shaft and adapted when the rock shaft is rocked in one direction to assume an operative position wherein they overlie the top surface of a work piece during a flanging operation, and releasable means for preventing reverse rocking of the rock shaft when the arms are in their operative position.

13. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a horizontally elongated bracket extending over and across said bottom arm, having the ends thereof mounted on the rods, and provided with a pair of vertically adjustable eye bolts with the eyes thereof at the top, a horizontal rock shaft overlying and extending parallel to the bracket and having the ends thereof journalled in the eyes of the bolts, a pair of laterally spaced arms connected to the rock shaft and adapted when the rock shaft is rocked in one direction to assume an operative position wherein they overlie the top surface of a work piece during a flanging operation, and releasable means for preventing reverse rocking of the rock shaft when the arms are in their operative position.

14. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a bracket extending over and across said bottom arm, having the ends thereof slidably mounted on the rods so that it is shiftable to and from said one shaft, and provided at its ends with a pair of vertically adjustable eye bolts with the eyes thereof at the top, a horizontal rock shaft overlying and extending parallel to the bracket and having the ends thereof journalled in the eyes of the bolts, a pair of laterally spaced arms having rollers rotatably mounted thereon, connected to the rock shaft so that they are adjustable to and from one another, and adapted when the rock shaft is rocked in one direction to assume an operative position wherein the rollers thereon overlie and engage the top surface of a work piece during a

flanging operation, and releasable means for preventing reverse rocking of the rock shaft when the arms are in their operative position.

15. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and a power driven mechanism for conjointly driving the shafts in opposite directions, of a pair of horizontal guide rods mounted on the structure and positioned along and outwards of opposite sides of said bottom arm, and a flanging hold-down attachment comprising a bracket extending over and across said bottom arm, having the ends thereof slidably mounted on the rods so that it is shiftable to and from said one shaft, and provided at its ends with a pair of adjustable eye bolts with the eyes thereof at the top, a horizontal rock shaft overlying and extending parallel to the bracket and having the ends thereof journaled in the eyes of the bolts, a pair of laterally spaced arms pivotally connected to the rock shaft so that they are capable of swinging to and from one another and adapted when the rock shaft is rocked in one direction to assume an operative position wherein they overlie the top surface of a work piece during a flanging operation, and releasable means for preventing reverse rocking of the rock shaft when the arms are in their operative position.

16. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and a power driven mechanism for conjointly driving the shafts in opposite directions, of a pair of horizontal guide rods mounted on the structure and positioned along and outwards of opposite sides of said bottom arm, and a flanging hold-down attachment comprising a horizontally elongated bracket positioned above and across said bottom arm, having the ends thereof mounted on the rods, and provided at its ends with vertically adjustable upstanding eye bolts with the eyes thereof at the top, a horizontal rock shaft overlying and extending parallel to the bracket and having the ends thereof journaled in the eyes of the bolts, a pair of arms connected to the shaft and adapted when the rock shaft is rocked in one direction to assume an operative position wherein they overlie the top surface of a work piece during a flanging operation, and releasable latch means between the bracket and the rock shaft for preventing reverse rocking of said rock shaft while the arms are in their operative position.

17. In a metal working machine of the character described, the combination with a C-shaped

supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a bracket positioned above and across said bottom arm, having the ends thereof slidably mounted on the rods so that it is shiftable to and from the one shaft, and provided at its ends with vertically adjustable upstanding eye bolts with the eyes thereof at the top, a horizontal rock shaft overlying and extending parallel to the bracket and having the ends thereof journaled in the eyes of the bolts, a pair of arms having rollers rotatably mounted thereon, adjustably connected to the shaft so that they are shiftable to and from one another, and adapted when the rock shaft is rocked in one direction to assume an operative position wherein the rollers thereon overlie and engage the top surface of a work piece during a flanging operation, and releasable latch means between the bracket and the rock shaft for preventing reverse rocking of said rock shaft while the arms are in their operative position.

18. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting flanging rolls, and power driven mechanism for conjointly driving the shafts in opposite directions, of a pair of horizontal guide rods mounted on the structure and positioned along and outwards of opposite sides of said bottom arm, and a flanging hold-down attachment comprising a bracket positioned above and across said bottom arm, having the ends thereof slidably mounted on the rods so that it is shiftable to and from the one shaft, and provided at its ends with vertically adjustable upstanding eye bolts with the eyes thereof at the top, a horizontal rock shaft overlying and extending parallel to the bracket and having the ends thereof journaled in the eyes of the bolts, a pair of arms having rollers rotatably mounted thereon, pivotally connected to the shaft to swing to and from one another, and adapted when the rock shaft is rocked in one direction to assume an operative position wherein the rollers thereon overlie and engage the top surface of a work piece during a flanging operation, and releasable latch means between the bracket and the rock shaft for preventing reverse rocking of said rock shaft while the arms are in their operative position.
